AIR CONDITIONING UNIT

Richard E. Allender, Davenport, Iowa, and Dale L. Selhost, Rock Island, Ill., assignors to American Air Filter Company, Inc., Louisville, Ky., a corporation of Delaware

Filed July 22, 1964, Ser. No. 80,973

Term of patent 14 years

(Cl. D62—4)

FIG. 1

FIG. 2

FIG. 3

FIGURE 1 is a perspective view of the air conditioning unit, showing our new design;

FIGURE 2 is an end elevational view taken from the right end of FIGURE 1;

FIGURE 3 is a top plan view of the air conditioning unit.

An end elevational view taken from the left end of FIGURE 1 would appear as a mirror image of FIGURE 2.

The rear of the unit is substantially plain.

The dominant features of the design reside in the portions shown in full lines.

We claim:

The ornamental design for an air conditioning unit, substantially as shown and described.
